ATTYS.

UNITED STATES PATENT OFFICE.

TIMOTHY WM. HICKEY, OF ABINGTON, MASSACHUSETTS.

HINGE.

1,336,780.

Specification of Letters Patent. Patented Apr. 13, 1920.

Application filed May 27, 1919. Serial No. 300,184.

To all whom it may concern:

Be it known that I, TIMOTHY W. HICKEY, a citizen of the United States, residing at Abington, in the county of Plymouth and 5 State of Massachusetts, have invented new and useful Improvements in Hinges, of which the following is a specification.

This invention relates to hinges of the type shown by the Upton and Gray Patent 10 No. 699,727, dated May 13, 1902, and it has for its object to provide improvements in a hinge of this type whereby its usefulness and general desirability are increased.

The invention is embodied in the improvements which I will now proceed to describe and claim.

Of the accompanying drawings, forming a part of this specification,—

Figure 1 is a side elevation of a hinge 20 embodying the invention.

Fig. 2 is an end view, parts being broken off.

Fig. 3 is a section on line 3—3 of Fig. 2.

Fig. 4 is a section on line 4—4 of Fig. 1.

25 Fig. 5 is a section on line 5—5 of Fig. 1.

Fig. 6 is a perspective view of the tongue washer.

Fig. 7 is a perspective view of the pintle.

Fig. 8 is a view similar to Fig. 1, showing a spring as a part of the adjustable abutment hereinafter referred to.

The same reference characters indicate the same parts in all of the figures.

The fixed member of the hinge includes a 35 plate or base 12, adapted to be attached to a door jamb, and a plurality of spaced apart pintle sockets 13, 14 and 15, adapted to receive a pintle 17. The upper socket 13 is internally polygonal and preferably square, as

40 shown by Fig. 4, and the pintle 17 has a correspondingly shaped upper portion 17^a fitting the socket 13, and prevented thereby from turning. The main portion of the pintle is cylindrical, and is formed to pass

45 through the intermediate fixed socket 14 and the lower fixed socket 15, and through the sockets of the swinging hinge member composed of a suitable base, preferably formed by straps 20 attachable to a door, and upper 50 and lower pintle sockets 21 and 22, formed to receive and turn on the cylindrical portion of the pintle.

The upper movable socket 21 is interposed between the upper fixed socket 13 and 55 the intermediate fixed socket 14, and the lower movable socket 22 is below the inter-

mediate socket and spaced from the lower fixed socket 15.

The pintle is provided between the movable socket 22 and the lower fixed socket 15 with a vertically adjustable abutment, which is preferably formed by an upper nut 24 and a lower nut 25, both engaged with a screw thread on the lower portion of the pintle, and a tongue washer 26 interposed 60 between said nuts, the tongue 27 of said washer engaging a longitudinal slot 28 in the pintle. The abutment aids in supporting the movable hinge member and the door to which said member is attached. The adjustability of the abutment enables its height 70 to be varied to compensate for wear of the meeting surfaces of the sockets 14 and 21, and the meeting surfaces of the socket 22 and nut 24.

75 Owing to the fact that the pintle is prevented from turning as described, it forms an immovable support for the nuts 24 and 25, so that the nuts which are locked on the pintle by their bearing on the non-rotatable 80 tongue washer, constitute an abutment which is free from liability to be accidentally displaced from any position to which it may be adjusted. The upper nut 24 is locked in any adjusted position by the lower nut 25 85 through the interposed washer, the lower nut acting as a jam or lock nut. As shown by Fig. 8, the abutment may be adapted to bear yieldingly against the lower movable socket 22 by a spring 30 interposed between 90 said socket and a cup washer 31 bearing on the nut 24.

The upper socket 13 of the fixed hinge member located above the upper socket 21 of the swinging hinge member confines the upper end of the pintle member in close proximity to the door, and thus prevents the upper movable socket 21 from sagging outwardly, so that the said socket and the door are firmly held in the proper relation to the 100 jamb.

I claim:

1. A hinge comprising a fixed member including a base adapted for attachment to a door casing, and a plurality of fixed spaced 105 apart pintle sockets, one at the upper end, another at the lower end, and the third between the ends of said base, the upper socket being internally polygonal, a pintle having a polygonal upper portion fitting the upper 110 socket and prevented from turning by the latter, and a cylindrical portion, passing

through the intermediate and lower fixed sockets, the pintle being provided with an adjustable abutment secured to its lower portion, between the lower and the intermediate fixed socket and vertically adjustable on the pintle, said adjustable abutment being formed by an upper nut and a lower nut, both engaged with a threaded portion of the pintle, and a tongue washer interposed between said nuts and engaged with a longitudinal groove in the pintle and a swinging member including a base, attachable to a door, and upper and lower movable pintle sockets on said base, the upper movable

socket being interposed between the upper 15 and intermediate fixed sockets, and the lower movable socket being interposed between the intermediate fixed socket and the adjustable abutment, the upper nut being locked in any adjusted position by the lower nut 20 through the interposed washer.

2. A hinge substantially as specified by claim 1, the said adjustable abutment including also a spring interposed between the upper nut and the lower movable socket. 25

In testimony whereof I have affixed my signature.

TIMOTHY WM. HICKEY.
